(57) **CLAIM**

The ornamental design for a carrier, as shown and described.

DESCRIPTION

FIG. 1 is a top front perspective view of a carrier showing the claimed design;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof;

FIG. 8 is a top front perspective view thereof in an open and extended configuration;

FIG. 9 is a right side view thereof in the open and extended configuration;

FIG. 10 is a left side view thereof in the open and extended configuration;

FIG. 11 is a front view thereof in the open and extended configuration;

FIG. 12 is a rear view thereof in the open and extended configuration;

FIG. 13 is a top view thereof in the open and extended configuration; and,

FIG. 14 is a bottom view thereof in the open and extended configuration.

The broken lines in the figures show portions of the carrier that form no part of the claimed design.

1 Claim, 14 Drawing Sheets
